SLIDING DOOR UNIT FOR SHOWER STALLS
OR THE LIKEMichael Lax, New York, N.Y., assignor to Formica
Corporation, Cincinnati, Ohio

Filed Mar. 9, 1971, Ser. No. 122,398

Term of patent 14 years

Int. Cl. D23—02

U.S. Cl. D23—69

FIG. 1

FIG. 2

FIG. 1 is a front perspective view of a sliding door unit for shower stalls or the like, showing my new design.

FIG. 2 is a plan section along the line 2—2 of FIG. 1. The broken line representation of a shower stall in FIGS. 1 and 2 is for purposes of illustration only.

I claim:

The ornamental design for a sliding door unit for shower stalls or the like, substantially as shown and described.
